(57) **CLAIM**

The ornamental design for a scroll member of a scroll fluid machine, as shown and described.

DESCRIPTION

FIG. 1 is a front view of a scroll member of a scroll fluid machine showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof in the direction of arrow 7 of FIG. 3;

FIG. 8 is a perspective view thereof in the direction of arrow 8 of FIG. 3;

FIG. 9 is a sectional view along line 9-9 of FIG. 3;

FIG. 10 is a sectional view along line 10-10 of FIG. 3; and, FIG. 11 is a reference top view wherein the shaded area represents the claimed portion of the present design.

The evenly spaced broken lines depict portions of the scroll member of a scroll fluid machine that form no part of the claimed design; the dash-dot broken lines define the boundary of the claimed design and form no part thereof.

1 Claim, 6 Drawing Sheets
